MEANS FOR COMPENSATING FOR WEAR ON SWAB PACKERS

Filed Feb. 18, 1928

INVENTOR:
John T. Phipps,
BY ATTORNEY:

UNITED STATES PATENT OFFICE.

JOHN T. PHIPPS, OF HUNTINGTON PARK, CALIFORNIA, ASSIGNOR OF ONE-FOURTH TO
MATTIE M. NEWCOMB.

MEANS FOR COMPENSATING FOR WEAR ON SWAB PACKERS.

Application filed February 18, 1928. Serial No. 255,383.

My invention relates to swabs such as are used in the oil-well industry.

Preparatory to putting a newly drilled oil-well on production it is necessary to bail out 5 the well or use a suitable swab for bringing to the surface of the ground the rotary mud or other substances filling the tubing in the well. This swab is so constructed that it will pass downward through the mud, and when 10 raised will bring a portion of the material in the tube to the surface of the ground. This swab has a suitable swab member thereon which engages the inner walls of the tube so as to form a fluid-tight sliding fit there- 15 with.

A tight engagement between the swab and the tubing is sometimes accomplished by longitudinally compressing the swab member to cause a transverse deformation thereof. 20 This is made possible by forming the swab member of suitable resilient or compressible material such as rubber or vulcanized canvas fabric. Such a swab member wears away relatively rapidly, and in the past it has been 25 necessary to frequently replace such members. Most of the wear on these swab members takes place at the lower end thereof. I have found it possible to form a swab having 30 a swab member which may be renewed when worn so as to be successfully reused for a number of times.

It is an object of my invention to provide a swab having an extremely long life.

It is another object of my invention to provide 35 a swab having a swab member which may be renewed when worn by a simple adjustment.

Another object of my invention is to provide 40 a swab having a swab member in which the entire length of the member may be utilized to accomplish a very efficient swabbing action.

I accomplish these ends by providing an 45 adjusting member adapted to pass over any worn portions of the swab member, this adjusting member compressing the swab member to cause engagement of a new portion of the swab member with the tube.

It is an object of my invention to provide 50 a swab having an adjusting member adapted to fit over a worn portion of a swab member to compress said member.

This adjusting member surrounds the worn portion of the swab member, thus elimi-

nating any tendency for the swab member to 55 blow out adjacent this worn portion.

It is an object of my invention to provide a swab which will not blow out when the swab member thereon becomes worn.

Other objects and advantages of my in- 60 vention will be made evident hereinafter.

I have illustrated one form of my invention in the accompanying drawing, this form being shown described with particular relation to the oil-well industry without in any 65 way limiting myself to this art.

Referring to the drawing,—

Fig. 1 is a partially sectioned view of the 70 swab of my invention.

Fig. 2 is an enlarged view showing the 75 manner in which such swabs commonly wear.

Fig. 3 is an enlarged view showing my 75 method of renewing the effectiveness of the swab member.

Fig. 4 is a horizontal sectional view taken on the line 4—4 of Fig. 1.

Fig. 1 illustrates a tubing 10 extending downward in an oil-well. A swab 11 is 80 adapted to be lowered in the tubing 10 and raise portions of the material in the tubing 10 to the surface of the ground. The swab 11 has a head 13 which is connected by a socket 14 to a suitable cable or other means which extends upward to the surface of the 85 ground and which is adapted to lower and raise the swab 11 in the tubing 10. A squared portion 15 is adapted to receive a suitable wrench when screwing the head 13 and the socket 14 together. Extending downward 90 from the head 13 is an inner tube structure 16 having an opening 17 therethrough, this tube structure, together with the head 13, forming a supporting structure 18. This opening communicates with the exterior of 95 the head 13 by suitable channels 19 extending therethrough. Resting against a shoulder 21 formed between the head 13 and the tube structure 16 is a shoulder member 22. The lower end of this shoulder member has an 100 annular groove 23 therein, this groove being bounded by radial walls 24 and 25. The shoulder member 22 completely surrounds the inner tube structure 16, and is adapted to receive the upper end of an upper swab mem- 105 ber 26, this swab member having an upper surface fitting the contour of the groove 23 and the radial walls 24 and 25. The lower

end of the upper swab member 26 is formed to engage the upper end of an upper compression member 28 which is threadedly secured to the tube structure 16, as indicated 5 by the numeral 29. Openings 30 in the upper compression member 28 form a means of longitudinally compressing the upper swab member 26 between the upper shoulder member 22 and the upper compression member 10 28, this longitudinal compression causing a transverse deformation of the swab member to cause this swab member to engage the inner surface of the tubing 10.

Slidably secured on the tube structure 16 15 and bearing against the upper compression member 28 is a lower shoulder member 35. The member 35 has an annular groove 36 bounded by radial walls 37 and 38 similar to the upper shoulder member 22. A lower 20 swab member 40 is adapted to fit in the annular groove 36 and to bear against these radial walls, this swab surrounding, and being slidably on, the inner tube structure 16. The lower end of the lower swab member 25 40 has radial walls 44 and 43 joined by a converging wall 45.

A sleeve member 47 is internally threaded to receive the inner tube structure 16, this sleeve member having an upper face 48 30 adapted to bear against the radial wall 43 of the lower swab member 40.

The sleeve member 47 is externally threaded to receive an adjusting member 49, this 35 adjusting member being much longer than the sleeve member 47, as best shown in Fig. 1. The upper end of the adjusting member has a frusto-conical face 52 which is adapted to engage the converging wall 45 of the swab member, and also has a radial wall 53 adapted 40 to engage the radial wall 44 of the lower swab member. Suitable openings 56 are formed in the sleeve member 47 and the adjusting member 49, these holes being adapted to receive suitable wrenches so that these members may be moved relative to each other or 45 relative to the inner tube structure 16. Similar openings 58 are formed in the extreme lower end of the adjusting member 49 and are utilized for advancing the adjusting member 49 relative to the sleeve 47.

Threadedly connected to the lower end of the inner tube structure 16, as indicated at 50, is a lower body 61, this body being kept from rotation relative to the tubing structure 55 16 by means of bolts 62 extending through elongated openings 63 in the tube structure. The lower end of the lower body 61 has a valve chamber 65 therein, this chamber being closed at its lower end by a plug 66 having 60 a seat 67 therein. This seat is adapted to receive a poppet valve 68 which is suitably journalled in a boss 69 of the plug 66. Nuts 70 on the poppet valve 68 prevent the valve from leaving the boss 69. The weight of the 65 poppet valve normally keeps the valve seated

on the seat 67, but should the pressure below the valve become greater than the pressure above, this valve will open into its dotted line position indicated by the numeral 72, thus allowing fluid to escape through openings 73 70 from the plug 66 into the valve chamber 65.

The operation of my invention is as follows:

The shoulder members, compression members, and swab members are suitably assembled 75 on the supporting structure 18. The upper compression member 28 is adjusted so that the upper swab member will slidably engage the inner surface of the tubing 10. The sleeve 47 and the adjusting member 49 80 are simultaneously moved relative to the inner tube structure 16 so that the lower swab member 40 is also longitudinally compressed so as to cause it to engage the inner walls 85 of the tube 10. The swab is then lowered 90 into the well to the required depth. During this lowering, any mud or other substance in the well opens the poppet valve 68 and flows upward through the inner tube 16, as indicated by the arrows 77. Thus, the swab 95 is easily lowered through this material. When the swab is raised, however, the poppet valve 68 closes and the material entrapped above the swab 11 will be raised 100 when the swab is raised due to the fluid-tight engagement between the swab members and the tubing.

I have found from experience that the lower swab member 40 receives the major portion of the wear and that this lower swab 105 member becomes worn in a manner similar to that illustrated in Fig. 2, this worn portion being indicated by the numeral 78. When this occurs, the swab member becomes ineffective, inasmuch as no longitudinal compressive stress is placed thereon which will deform the swab member so as to engage the tubing 10. Furthermore, there is a danger 110 of the swab member blowing out through this worn portion. When the swab member becomes worn in a manner illustrated in Fig. 2, a suitable wrench is placed in the openings 58, and the adjusting member 49 is 115 moved relative to the sleeve member 47. This movement is continued until the radial wall 53 and the frusto-conical portion 52 of the adjusting member come into engagement with an upper end 79 of the worn portion 78. Further upward movement of the adjusting member will put a longitudinal compressive stress on the swab member 120 which will again cause it to deform so as to engage the inner walls of the tubing 10. It should be noted that the adjusting member at this time surrounds the worn portion, 125 thus preventing a blowout of the swab member.

This renewed operation may be continued until the worn portion 78 reaches the upper end of the swab member, at which time it 130

is necessary to insert a new member. The life of the average swab member is increased many fold by the use of my invention, and where it was previously necessary to 5 discard a swab member when it became worn in a manner indicated in Fig. 2, my invention makes it practical to readjust the adjusting member and recompress and reinforce the swab member so that it is again 10 effective in swabbing the tube 10.

The sleeve 47 may be secured to the lower body 61, instead of being separated therefrom, without departing from the spirit of my invention. Furthermore, the adjusting 15 member 49 may be made as long as desired, so as to be used on any length of swab member. Furthermore, a similar adjusting member may be placed on the upper compression member 28, if desired, and I am not limited 20 to the use of two swab members as illustrated.

I claim as my invention:

1. In a swab adapted to form a fluid-tight fit with a tubing, the combination of: a supporting structure; a swab member carried by said supporting structure; means for longitudinally compressing said swab member to cause said member to engage said tubing, said swab member becoming worn through 30 said engagement; and an adjusting member longitudinally movable relative to said swab member to engage a worn portion of said swab member whereby said swab member again engages said tubing.

2. In a swab adapted to form a fluid-tight fit with a tubing, the combination of: an inner structure; a shoulder surrounding said inner structure; a swab member surrounding said inner structure; a sleeve member movable 40 relative to said inner structure, said sleeve member compressing said swab member against said shoulder; and an adjusting member movable relative to said sleeve member to engage said swab member.

3. In a swab adapted to form a fluid-tight fit with a tubing, the combination of: an inner structure; a shoulder surrounding said inner structure; a swab member surrounding said inner structure; a sleeve member movable relative to said inner structure, said sleeve member compressing said swab member against said shoulder; and an adjusting member movable relative to said sleeve member, said adjusting member filling a worn 50 portion of said swab member to cause a new fit between said swab member and said tubing.

4. In a swab adapted to form a fluid-tight fit with a tubing, the combination of: an inner structure; a shoulder surrounding said

inner structure; a swab member surrounding said inner structure; a sleeve member threadedly carried by said inner structure, said sleeve member compressing said swab member against said shoulder; and an adjusting member threadedly carried by said sleeve member to engage said swab member.

5. In a swab adapted to form a fluid-tight fit with a tubing, the combination of: an inner structure; a shoulder surrounding said inner structure; a swab member surrounding said inner structure; a sleeve member threadedly carried by said inner structure, said sleeve member compressing said swab member against said shoulder; and an adjusting member threadedly carried by said sleeve member, said adjusting member filling a worn portion of said swab member to cause a new fit between said swab member and said tubing.

6. In a swab adapted to form a fluid-tight fit with a tubing, the combination of: an inner structure; a shoulder surrounding said inner structure; a swab member surrounding said inner structure; a lower body adjustable relative to said inner structure; a sleeve member between said lower body and said swab member, said sleeve member compressing said swab member against said shoulder; and an adjusting member movable relative to said sleeve member to engage said swab member.

7. In a swab adapted to form a fluid-tight fit with a tubing, the combination of: a supporting structure; a swab member carried by said supporting structure and adapted to slidably engage said tubing; and means embracing an end portion of said swab member and slidably adjustable on said end portion to further embrace said end portion to compensate for wear of the adjacent tubing engaging surface of said swab member.

8. In a swab adapted to form a fluid-tight fit with a tubing, the combination of: a supporting structure; a swab member carried by said supporting structure and adapted to slidably engage said tubing; and an adjusting member embracing an end portion of said swab member and longitudinally adjustable relative to said supporting structure and to said end portion to further embrace said end portion to compensate for wear of the adjacent tubing engaging surface of said swab member.

In testimony whereof, I have hereunto set my hand at Los Angeles, California, this 10th day of February, 1928.

JOHN T. PHIPPS.
